Luis M. Church

UNITED STATES PATENT OFFICE.

LOUIS M. CHURCH, OF WASHINGTON, DISTRICT OF COLUMBIA.

ATTACHMENT FOR FILING-CABINETS.

1,369,884.

Specification of Letters Patent.

Patented Mar. 1, 1921.

Application filed January 5, 1920. Serial No. 349,620.

(FILED UNDER THE ACT OF MARCH 3, 1883, 22 STAT. L., 625.)

To all whom it may concern:

Be it known that I, LOUIS M. CHURCH, a citizen of the United States, and a resident of Washington, District of Columbia, have 5 invented an Improvement in Attachments for Filing-Cabinets, of which the following is a specification.

The invention described herein may be used by the Government, or any of its officers or employes in prosecution of work for 10 the Government, or by any other person in the United States, without payment of any royalty thereon.

This invention relates to improvements in 15 attachments for filing cabinets and more particularly to a shelf adapted to be detachably connected to a drawer of the filing cabinet. The peculiar advantages of this invention comprise lightness in construction, portability, cheapness in manufacture 20 and adaptability for use upon a great variety of cabinets.

Referring more particularly to the drawings:

25 Figure 1 represents a perspective view of the filing cabinet provided with my improved attachment.

Fig. 2 is a perspective view of the shelf, and

30 Fig. 3 is a front elevation of the modified form of the invention.

In the drawings 1 represents a filing cabinet of well known construction provided with drawers 2. Attached to the upper edge

of one of the drawers by means of hangers 35 3, provided at their upper ends with hooks 4 is a shelf 5. This shelf is secured to the hangers 3 at its underside by screws 6, and between said hangers there is attached by means of an angle iron 7 a downwardly projecting rectangular block 8 which is designed when the shelf is in position to be embraced by the drawer handle. This lower block not only serves to prevent the shelf 40 from bending downwardly but operates to 45 center the shelf with reference to the drawer end.

Instead of the block 8 two iron bars 9 may be attached to the lower face of the shelf as is shown in Fig. 3. While the hangers 3 serve to aid in keeping the shelf in proper position it has been found in many cases that they may be omitted, the bars 9 serving as the sole support. These bars 50 may be obviously of such width as to fit 55 snugly into the handle of the drawer.

Having thus described the invention what is claimed as new and desired to secure by Letters Patent is:

1. In a cabinet, the drawer provided with 60 a center loop handle, a shelf seated upon said handle and hangers securing said shelf and overhanging the top of the drawer.

2. A shelf provided with a depending bracket upon the lower side and upwardly 65 projecting hangers located on the opposite sides of said bracket.

LOUIS M. CHURCH.
